DESIGN FOR A LIGHT DIFFUSING TORCHIERE SHADE

Richard Orth, Philadelphia, Pa., assignor to Gill Glass & Fixture Company, Philadelphia, Pa., a corporation of Delaware

Application February 24, 1938, Serial No. 75,378

Term of patent 7 years

To all whom it may concern:

Be it known that I, Richard Orth, a citizen of the United States of America and a resident of Philadelphia, in the county of Philadelphia and State of Pennsylvania, have invented a new, original, and ornamental Design for a Light Diffusing Torchiere Shade, of which the following is a specification, reference being had to the accompanying drawing, forming a part thereof.

In the drawing:

The figure is a perspective view of the light

diffusing torchiere shade showing my new design.

The design is characterized by a light diffusing torchiere shade of substantially the contour shown and having an opaque band A and a light diffusing bottom composed of a series of steps with vertical side walls and flat intermediate areas.

I claim:

The ornamental design for a light diffusing torchiere shade, as shown and described.

RICHARD ORTH.
